UNITED STATES PATENT OFFICE

111,807

DESIGN FOR A SPRAY NOZZLE

Edgar Bartram Frame, Philadelphia, Pa., assignor to Monarch Manufacturing Works, Inc., Philadelphia, Pa., a corporation of Delaware

Application August 6, 1938, Serial No. 79,152

Term of patent 14 years

To all whom it may concern:

Be it known that I, Edgar Bartram Frame, a citizen of the United States and a resident of Philadelphia, in the county of Philadelphia and State of Pennsylvania, have invented a new, original, and ornamental Design for a Spray Nozzle, of which the following is a specification, reference being had to the accompanying drawing, forming a part thereof.

Figure 1 is a front elevational view of the spray nozzle showing my new design.

Figure 2 is a bottom plan view,
Figure 3 is a rear elevational view,
Figure 4 is a rear end view, and
Figure 5 is a front end view.

I claim:

The ornamental design for a spray nozzle, as shown.

EDGAR BARTRAM FRAME.
